UNITED STATES PATENT OFFICE

153,349

DESIGN FOR A BOTTLE OPENER

Oscar R. Galter, Chicago, Ill.

Application January 10, 1947, Serial No. 136,049

Term of patent 14 years

(Cl. D44—29)

To all whom it may concern:

Be it known that I, Oscar R. Galter, a citizen of the United States of America, residing at 172 North Union Street, city of Chicago, in the county of Cook, State of Illinois, have invented a certain new, original, and ornamental Design for a Bottle Opener, of which the following is a specification, reference being had to the accompanying drawing, forming part thereof.

Referring to the drawing, Fig. 1 is a top plan view of a bottle opener embodying my new design; Fig. 2 is a side elevational view; Fig. 3 is a bottom view; Fig. 4 is a front end view and Fig. 5 is a rear end view of the same.

I claim:

The ornamental design for a bottle opener, substantially as shown.

OSCAR R. GALTER.
